ATTORNEYS

UNITED STATES PATENT OFFICE.

JOSEPH C. DAMRON, OF ROANOKE, VIRGINIA.

BALING-PRESS.

No. 914,336.

Specification of Letters Patent. Patented March 2, 1909.

Application filed October 2, 1908. Serial No. 455,884.

To all whom it may concern:

Be it known that I, JOSEPH C. DAMRON, a citizen of the United States, and a resident of Roanoke, in the county of Roanoke and State of Virginia, have invented certain new and useful Improvements in Baling-Presses, of which the following is a specification.

This invention is an improvement in baling presses and relates especially to that class of presses illustrated in my former patent #749,662, dated January 12, 1904.

The present invention provides a machine adapted to be operated by power, such as horse power or the like and to furnish tripping devices for automatically releasing the shifting and locking devices for the gear mechanism when the plunger reaches the end of its pressing stroke.

The invention consists in certain novel constructions and combinations of parts as will be hereinafter described and claimed.

In the drawings, Figure 1 is a top plan view, partly broken away, of a baling press embodying my improvements. Fig. 2 is a side elevation of a press. Fig. 3 is a detail perspective view of the tripping devices, and Fig. 4 is a longitudinal section of the press, partly broken away, and showing a somewhat different construction of the tripping devices from that shown in Figs. 1 and 2, and Fig. 5 is a detail view illustrating a construction whereby gasoline or other engines may be utilized as the operating power.

The plunger A operates in the bale box B and is provided with laterally extending studs A', which may be the extended ends of a shaft. These studs A' project through slots B' in the bale box A, and are arranged to operate at the end of the pressing stroke 40 of the plunger upon hooked ends C', of bars C sliding longitudinally in guides D and extending to a point in rear of the bale box where they are connected at C² with the lower arms of the lever C³ pivoted at C⁴ and having a cross bar C⁵ operating in front of the locking and shifting lever E to push said lever to the position in which it will shift the gear devices relatively to each other in such manner as to move the gear devices out of mesh as will be more fully described herein-after.

As shown I provide the plunger with rack devices F movable in guides G in the bed frame of the press, and these racks F constitute a part of the gearing co-operating with

gear devices H which are mounted in a gear frame I pivoted or hinged at I', so that the said gear frame may be lowered to the full line position shown in Figs. 2 and 4, in which its gears H will mesh with the racks F of the plunger, or the said frame I may be lifted at its front end to move its gear wheels H out of engagement with the racks F to permit the plunger to be retracted by the spring J.

The shaft H' carrying the gears H and an intermediate ratchet wheel H² engaged by a pawl H³ is extended beyond the bale box and receives a gear H⁴ which is meshed by a pinion H⁵, and the said pinion H⁵ has its shaft H⁶ coupled at H⁷ with a drive shaft K' leading from a horse power K² so the shaft H' may be operated by power to move the plunger as desired. This is a simple convenient means for applying power to the machine and the power may operate continuously as the rocking of the gear frame on its hinge or pivot I' effects a lifting of the gear H⁴ out of mesh with the pinion H⁵ so that when the gears H are lifted out of mesh with their racks F, the gear H⁴ will also be lifted out of mesh with its drive pinion stopping the operation of the shaft H' at such time.

The locking and shifting lever E is pivoted at E', has a cross bar E² which may be adjusted above the swinging end of the gear frame to lock the said frame in position for use and such lever E is also provided with a crank arm projection E³ which engages the swinging end of the gear frame I after the cross bar E² has been swung over the said hinged end, so that the crank arm or projection E³ will lift the swinging end of the gear frame to such extent as to move the gear wheels H out of mesh with the rack bars F so the latter can slide rearwardly in the readjustment of the plunger by the returning spring J.

In the operation of the described construction it will be noticed that when the parts are in the position shown in Fig. 2, and the shaft H' is operated to turn its gears H to operate upon racks F, the plunger will be advanced to press the hay or other material until the studs or projections A' on the plunger strike the hook C' when the parts will be operated to the dotted line position shown in Fig. 2. Thus the rods C will be moved by the engagement of the plunger studs A' at C' rearwardly and will rock the lever C³ to the dotted line posi-

tion shown in Fig. 2 forcing the locking and shifting lever C to the dotted line position shown in Fig. 2, thus releasing the gear frame I and lifting said frame by the action of the crank arm E³ to the dotted line position shown in Fig. 2, thus lifting the gears H out of mesh with the rack bars F and permitting the readjustment of the plunger to its initial position by the action of the spring J.

10 If in operation at any time the man feeding the machine should get his fork in advance of the plunger or other obstruction find its way into the press box the operator can instantly move the locking and shifting lever E by hand to the dotted line position shown in Fig. 2, thus not only throwing the drive mechanism out of operation, but also moving the gear devices out of mesh so the plunger can be instantly returned to its initial position by the action of the spring J. This is important in avoiding injury to the machinery or to the operators as will be understood by those skilled in this art.

If desired a gasoline or other engine might be used for driving the pinion H⁵, the shaft of which may for such purpose be provided with a sprocket or band wheel to receive a chain or belt from the engine as will be understood from Fig. 5 of the drawings. In this Fig. 5, the shaft H⁵ is shown as supplied with a sprocket wheel H¹⁶, and a band wheel H¹⁷ so power may be applied thereto by a chain or belt as preferred.

It will be understood that the automatic releasing of the gearing is an important feature of my invention, and this automatic releasing is secured from the plunger.

Manifestly, instead of the particular construction shown in Figs. 1, 2 and 3, I may use the construction shown in Fig. 4, in which a rod L is connected at L' with the plunger and extends thence to a point in advance of the locking and shifting lever and has a hook or projection L² which engages with the lower end of the locking and shifting lever as the plunger reaches the end of its pressing stroke and shifts the said locking and shifting lever to its position as will be understood from Fig. 4 of the drawings.

50 Manifestly, my baling press may be used for baling any balable substance or material and may if desired be made in different sizes to adapt it for the use of more or less power according to the material for which any particular press may be especially designed.

I claim:

1. The combination of a plunger, rack devices connected with the plunger, a frame having gear devices meshing with the rack devices and movable whereby the said gear devices may be set into and out of mesh with the rack devices, a locking and shifting lever operating upon said gear frame, a releasing lever having means for shifting said locking and shifting lever from locked position, and a

rod connected with said releasing lever and having means for operation by the plunger, substantially as set forth.

2. In a press the combination with a plunger, and rack devices connected therewith, of a frame movable relatively to the rack devices of the plunger and supporting a gear movable with the frame into and out of mesh with the rack devices of the plunger, a locking and shifting lever operating upon said gear frame and having means whereby when it is shifted from locked position it will shift the gear frame to free its gear devices from mesh with the rack devices of the plunger, and a rod sliding longitudinally in the direction of movement of the plunger and arranged for operation thereby to shift the releasing lever from locked position, substantially as set forth.

3. The combination, in a press, of a plunger, rack devices connected therewith, gear devices meshing with the rack devices, a frame supporting said gear devices and movable whereby it may be moved to set its gear devices into and out of mesh with the rack devices of the plunger, a locking and shifting lever having means for locking the gear frame in one position and means for shifting it from said position, and a slide rod arranged for operation by the plunger and provided with means for operating the locking and shifting lever, substantially as set forth.

4. The combination in a baling press, of a drive pinion, a plunger, rack devices connected with the plunger, a gear frame movably supported, a gear wheel carried by said frame and movable therewith whereby it may be set into and out of mesh with the rack devices of the plunger, and a gear wheel carried by the gear frame and movable therewith whereby the gear wheel may be set into and out of mesh with the drive pinion, means for locking the gear frame in operative position, and means for shifting it from said position, substantially as set forth.

5. The combination with a plunger having rack devices, of a gear frame having gearing meshing with the rack devices of the plunger, said gear frame being movable whereby its gearing may be set into and out of mesh with said devices, a drive gear carried by the gear frame and movable therewith whereby it may be set into and out of mesh with a drive pinion, and a drive pinion meshing with said gear when the gear frame is in operative position, substantially as set forth.

6. The combination, in a baling press, of a plunger having rack devices, a gear frame hinged at one end and movable at its other end, a gearing carried by the gear frame and movable into and out of mesh with the rack devices of the plunger, and a shaft connected with said gearing and extending laterally, a gear wheel on such lateral extension of the

shaft, and a drive pinion meshing with said gear wheel, the latter moving into and out of mesh with said pinion as the gearing of the movable gear frame is moved into and out of mesh with the rack devices of the plunger, substantially as set forth.

7. The combination, in a press, of a plunger, rack devices connected with the plunger, gear devices meshing with the rack devices, 10 a gear frame carrying said gear devices and movable whereby the gear devices may be set into and out of mesh with the rack de-

vices, a locking and shifting lever operating upon said gear frame, a releasing lever having a cross bar adapted to shift said lever 15 from locked position, and a rod connected with said releasing lever and having means for operation by the plunger, substantially as set forth.
